US00D543174S

(12) **United States Design Patent** (10) **Patent No.:** **US D543,174 S**
(45) **Date of Patent:** **** May 22, 2007**

(54) **MOBILE PHONE**

(75) Inventor: **Ji Young Kim**, Seoul (KR)

(73) Assignee: **LG Electronics Inc.**, Seoul (KR)

(**) Term: **14 Years**

(21) Appl. No.: **29/238,258**

(22) Filed: **Sep. 14, 2005**

(30) **Foreign Application Priority Data**

Mar. 15, 2005 (KR) 30-2005-0008453

(51) **LOC (8) Cl.** **14-03**

(52) **U.S. Cl.** **D14/138; D14/341**

(58) **Field of Classification Search** D14/137-138, D14/144, 156, 147-148, 247-248, 341-347,

D14/496; D21/329, 331, 333; 379/433.01-433.13;

348/14.01, 14.02, 376; 455/556.1, 556.2,

455/566, 575.1, 575.4, 90.3; D16/208

See application file for complete search history.
